(57) **CLAIM**

The ornamental design for a pair of earphones, as shown and described.

DESCRIPTION

FIG. 1 is a front, right, and top perspective view of a right earphone of a pair of earphones showing my design, shown separately to show aspects of the design that are not visible when combined;

FIG. 2 is a rear, left, and top perspective view thereof;

FIG. 3 is a rear elevation view thereof;

FIG. 4 is a front elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a front, right, and bottom perspective view of a left earphone of the pair of earphones showing my design, shown separately to show aspects of the design that are not visible when combined;

FIG. 10 is a rear, left, and top perspective view thereof;

FIG. 11 is a rear elevation view thereof;

FIG. 12 is a front elevation view thereof;

FIG. 13 is a right side elevation view thereof;

FIG. 14 is a left side elevation view thereof;

FIG. 15 is a top plan view thereof;

FIG. 16 is a bottom plan view thereof;

FIG. 17 is a front perspective view of the pair of earphones showing the new design; and,

FIG. 18 is a rear perspective view thereof.

The broken lines depict portions of the pair of earphones that form no part of the claimed design.

1 Claim, 18 Drawing Sheets
